R. G. RICHARDSON

MEASURED SERVICE TELEPHONE SYSTEM

Filed Nov. 15, 1919

Inventor
Rodney G. Richardson

W. F. Wallace Atty:

UNITED STATES PATENT OFFICE.

RODNEY G. RICHARDSON, OF CHICAGO, ILLINOIS, ASSIGNOR TO AUTOMATIC ELECTRIC COMPANY, OF CHICAGO, ILLINOIS, A CORPORATION OF ILLINOIS.

MEASURED-SERVICE TELEPHONE SYSTEM.

Application filed November 15, 1919. Serial No. 338,378.

To all whom it may concern:

Be it known that I, RODNEY G. RICHARDSON, a citizen of the United States of America, and a resident of Chicago, in the county of Cook and State of Illinois, have invented certain new and useful Improvements in Measured-Service Telephone Systems.

My invention relates in general to measured service telephone systems, but more particularly to automatic party line measured service systems, and the principal object of the invention may be stated to be, specifically, the provision of a system where-
10 in each station on a party telephone line is provided with a meter at the exchange, and wherein each meter is adapted to be separately connected for registering calls whenever its associated station is in use.
15 Incidental objects consist in the provision of improved circuit arrangements whereby the foregoing is accomplished as efficiently as possible, all of which is described fully in the following specification, and illustrated in
20 the accompanying drawing forming a part thereof.

Referring to the drawing the layout of the system shown therein is as follows: The telephones A' and A² are connected in bridge of the line conductors 2 and 3 in the usual manner, the line being what is commonly known as a 2 party line. At the exchange the line terminates in the rotary line switch indicated by reference character C, which is of well known construction, except as modified by my invention, and which is provided for the purpose of extending the line responsive to the removal of the receiver at a calling station to a trunk line terminating in an idle selector switch. One such trunk line comprising conductors 41, 43, inclusive, is shown extending to the selector H. Selector switches, as is well known, have the function of extending calling lines to idle connector switches in desired hundreds groups, and there may be only one selector or a plurality in serial relation, in any given connection, depending on the size of the system.
50 As shown herein, one of the trunk lines to which the selector H has access extends to the connector I, which is operable to complete connection to any one of a group of

100 lines, one of which is the line extending to station A³. Line, selector, and connector switches are well known in the art, and since they have nothing especial to do with my invention, most of the circuit details have for simplicity been omitted.

The meters or call registers M' and M² are associated, respectively, with substations A' and A² and are located at any preferred point in the exchange, as for example in a cabinet, or they may be mounted on the switchboard adjacent to the line switches. The meters are operated by relays in the selector trunks, such as the relay 29, and selection of the proper meter in accordance with the calling station is accomplished by the relay 5 of the line switch C, as will now be explained.

Suppose that the subscriber at station A' desires to call the subscriber at station A³, in which case it will be necessary to actuate meter M' at the proper time to register the call. Upon the removal of the receiver a circuit is completed for relay 5 and the slow acting line relay 6 of line switch C as follows: ground at G', winding of relay 5, resting contact of armature 13 and the said armature, line conductor 3, substation A', line conductor 2, armature 15 and its resting contact, and the winding of relay 6 to battery. Relays 5 and 6 are energized simultaneously, the former opening the contacts controlled by its armatures 10 and 11, and at its armature 12 shifting the connection of wiper 22 from the winding of meter M² to the winding of meter M'; while the line relay 6 at its armature 9 closes the following circuit for the switching relay 4: ground at G², armature 9 and its right hand working contact, lower winding of relay 5, winding of relay 4, and the winding of the motor magnet 7 to battery. At the same time the line relay, by means of its armature 8, connects the test wiper 23 to the above circuit at a point between the winding of the relay 4 and the motor magnet 7. The operation now depends on whether the trunk line with which the wipers of the line switch C are in engagement, is busy or is not busy. If the trunk line is busy, the test contact 27, will be grounded, the switching relay 4 will be short-circuited and prevented from energizing, and the motor magnet 7, which in-

terrupts its own circuit, will be operated to advance the switch wipers 21—24, inclusive, step-by-step in search of an idle trunk line.

However, we may assume that when the 5 operation of the line switch was initiated, its wipers were in engagement with the trunk line extending to selector H, as shown, and that this trunk line was idle. Under these 10 circumstances no rotation of the switch will take place, owing to the high resistance of the switching relay 4, and the said relay 4 will energize at once, with the result that the line conductors 2 and 3 are disconnected from the windings of relays 6 and 5, respectively, and are extended by way of armatures 15 and 13, wipers 21 and 24, and conductors 41 and 43 to the selector H. Upon 15 the establishment of connection with selector H, the line and release relays of the selector (not shown but corresponding to relays 52 and 53 of connector I) are energized in the usual manner to ground the conductor 42, whereby a holding circuit is established for the switching relay 4 of the 20 line switch as follows: grounded release trunk conductor 42, test contact 27, test wiper 23, armature 14 and its working contact, lower winding of relay 5, winding of relay 4, and the winding of the motor magnet 7 to battery. Thus it will be seen that 25 relays 4 and 5 are maintained energized, the latter relay maintaining the connection to meter M' so that it can be operated at the proper time to register the call.

30 So far the circuits have been described in considerable detail in order to make the invention perfectly clear, but since the remainder of the equipment to be described in the connection is old this will no longer 35 be necessary. It will suffice to say that the subscriber at station A' will now operate his calling device in accordance with the digits in the number assigned to station A³, whereupon the selector H and a connector 40 switch, assumed to be the connector I, are operated to complete the desired connection and signal the called subscriber.

45 Upon the removal of the receiver the back bridge relay 51 of the connector is energized, this relay having the well known function of reversing the direction of current flow in the calling line. This brings us to the consideration of the means for actuating the meter M' to register the call. The 50 trunk line extending to selector H is provided with an electro-polarized relay 29 which has a polarizing winding of high resistance and few turns through which current flows from the grounded release trunk conductor 42 while the trunk is in use. This 55 winding and the right hand winding, which is in series with the conductor 43, are in opposition during the establishment of the connection and until the called subscriber 60 answers, relay 29 therefore remaining in-

operative. When the called man answers and current is reversed in the calling line, the windings of relay 29 assist each other and the said relay is operated, with the result that at armature 31 the right hand winding is short-circuited (so as not to interfere with the talking circuit), while at armature 30 a circuit is closed for meter M' as follows: ground at G³, armature 30 and its working contact, wiper 22 armature 16 and its working contact armature 12 and its working contact, and the winding of the magnet of meter M' to battery. The meter magnet thereupon attracts its armature, and upon the release of the connection, which takes place in the usual manner when the receiver is replaced at station A', the armature is retracted to advance the number wheels to register the call.

65 It will now be explained how the meter M² is operated to register a call initiated from the station A². Although station A' is an ordinary automatic substation with no special equipment the other station on the line, station A² must be provided with 70 means for preventing the energization of relay 5 of line switch C when the receiver is removed. This means consists of an arrangement of switch hook springs whereby the line conductor 2 is grounded as the switch hook starts to rise and before the circuit is completed through the substation, the connection to ground being broken after the line circuit has been completed and just before the switch hook has reached its 75 uppermost position.

80 Suppose now that the subscriber at station A² desires to make a call. When the receiver is removed a circuit is completed for line relay 6 of the line switch C as follows: ground at G⁴, contact springs 55 and 56, switch hook, line conductor 2, armature 15 and its resting contact, and the winding of line relay 6 to battery. Responsive 85 to the closure of the above circuit, line relay 6 energizes as in the former case, when station A' was calling, but now since relay 5 is not energized, relay 6 closes a circuit by means of its armature 9 and left hand working contact which supplies direct ground to line conductor 3 and thus short circuits the upper winding of relay 5 and prevents it from energizing an instant later when the lines are closed at the telephone 90 and the ground connection is broken. Additional circuits causing the operation of the switch to select an idle trunk are closed by line relay 6 as previously described and the operation proceeds as before until the connection is finally completed, relay 5 not being energized in series with the switching relay 4 because its lower winding is short circuited at armature 11. It will be seen 95 therefore that when the called subscriber answers and the polarized relay 29 is oper-

ated, since armature 12 of relay 5 is in retracted position, the meter M^2 will be actuated and a call will be charged against the proper party, the subscriber at station A².

What I claim is:

1. In a telephone system, a two party line, a meter at the exchange normally connected for registering calls from one of the stations on said line, a second meter for registering calls from the other station, a meter selecting relay for switching the connection from one meter to the other, full metallic and ground return circuits closed at the two stations, respectively, when calling, for controlling said relay, means at the corresponding station for opening the ground circuit during conversation, and means controlled by the response of the called subscriber for operating the connected meter.
2. In a telephone system, a two party line, a meter at the exchange normally connected for registering calls from one of the stations on said line, a second meter for registering calls from the other station, a meter selecting relay for switching the connection from one meter to the other, means for energizing said relay over the line when a call is made from one of said stations, a second relay for preventing the operation of said selecting relay, and means for energizing said second relay over the line when a call is made from the other of said stations.
3. In a telephone system, a two party line, a meter at the exchange normally connected for registering calls from one of the stations on said line, a second meter for registering calls from the other station, a meter selecting relay for switching the connection from one meter to the other, a second relay, means for energizing said relays in series when a call is made from one of said stations, means for energizing said second relay independently when a call is made from the other station, and means controlled by said second relay for preventing the energization of said selecting relay.
4. In a telephone system, a two party line, a meter at the exchange normally connected for registering calls from one of the stations on said line, a second meter for registering calls from the other station, a meter selecting relay for switching the connection from one meter to the other, an individual line relay for said line, means for energizing both relays simultaneously when a call is made from one of said stations, means for energizing said line relay independently when a call is made from the other station, and a circuit closed by said line relay when the selecting relay is deenergized for short circuiting the said selecting relay.
5. In a telephone system, a two party line, a meter at the exchange normally connected for registering calls from one of the

stations on said line, a second meter for registering calls from the other station, a meter selecting relay for switching the connection from one meter to the other, means for energizing said relay over the line when a call is made from one of the stations on said line, means for temporarily grounding one side of the line when the call is made from the other station, and means responsive to said grounding for preventing the operation of said relay.

6. In a telephone system, a two party line, a meter at the exchange normally connected for registering calls from one of the stations on said line, a second meter for registering calls from the other station, a meter selecting relay for switching the connection from one meter to the other, a rotary step-by-step switch for extending said line when calling, means for energizing said relay when the call is made from one of said stations, and means for short circuiting the windings of said relay to prevent its operation when the call is made from the other station.

7. In a telephone system, a two party line, a meter at the exchange normally connected for registering calls from one of the stations on said line, a second meter for registering calls from the other station, a meter selecting relay for switching the connection from one meter to the other, a rotary step by step switch for extending said line when calling, a line relay for said switch connected in series with said selecting relay when the call is made from a particular one of said stations, means for closing a circuit including said line relay only when the call is made from the other one of said stations, and means responsive to a reversal of current for operating the connected meter.

8. In a telephone system, a party line, a meter at the exchange for each station on the line, a rotary step by step trunking switch for extending said line when calling, a relay in said switch controlled over the line when a call is initiated, and circuit connections whereby when said relay is short circuited only one of said meters may be operated, and whereby when said relay is energized another of said meters may be operated.

9. In a telephone system, a party line, a meter at the exchange for each station on the line, a rotary step-by-step trunking switch for extending said line when calling, a relay in said switch for determining which of said meters is to be actuated, means for energizing said relay when the call is made from one of the stations on said line, and means for preventing the energization of said relay by short circuiting the same when the call is made from another station on said line.

10. In a telephone system, a two-party line, two meters at the exchange for registering calls from said line, a relay for deter-

mining which of said meters is to be operated, means for energizing said relay when a call is made from one of the stations on said line, and means for short circuiting said relay to prevent its energization when a call is made from the other station on said line.

11. In a telephone system, a two-party line, two meters at the exchange for registering calls from said line, a relay for determining which of said meters is to be operated, means for energizing said relay when a call is made from one of the stations, a holding circuit for maintaining said relay operated, a cut off relay included in said holding circuit in series with said first relay, and means for preventing the operation of said meter selecting relay when a call is made from the other station.

12. In a telephone system, a two-party

line, two meters at the exchange for registering calls from said line, a meter selecting relay, a line switch for extending said line when calling, a line relay and a cut off relay in said switch, means for operating the line relay in series with the meter selecting relay when a call is made from one of the stations, a holding circuit for said selecting relay in series with said cut off relay, means for operating said line relay alone when a call is made from the other station on said line, and means controlled by said line relay when operated alone for preventing said selecting relay from energizing over said holding circuit.

Signed by me at Chicago, Cook County, State of Illinois, this 12th day of November, 1919.

RODNEY G. RICHARDSON.
